INVENTOR
WILLIAM I. NYE.

BY *Charles H. Sibley*
ATTY.

UNITED STATES PATENT OFFICE.

WILLIAM I. NYE, OF SAN FRANCISCO, CALIFORNIA.

PRESS FEED GUIDE.

Application filed October 10, 1927. Serial No. 225,303.

My invention relates to improvements in guides arranged to be detachably secured upon the platen sheets of presses for registering sheets with forms to be printed thereon.

5 The primary object of my invention is to provide an improved press feed guide.

Another object is to provide an improved guide which may be quickly applied and easily adjusted to a desired position.

10 A further object is to provide an improved device of the character described which may be easily and effectively locked in adjusted position.

A further object is to provide an improved 15 guide which will facilitate adjustment to a desired position, and which will permit a relatively wide adjustment from an initial setting without removing the guide.

A further object is to provide an improved 20 construction which will hold the guide in close engagement with the platen paper and prevent the movement of sheets under the edge of the guide while the press is in operation.

Another object is to provide an improved 25 device provided with an adjustable retaining tongue arranged to be clamped in adjusted position simultaneously with the clamping of the guide upon the platen sheet.

A still further object is to provide an improved 30 device of simple and efficient construction which can be manufactured economically and which will be durable and efficient in operation.

I accomplish these and other objects by 35 means of the improved device disclosed in the drawings forming a part of the present application wherein like characters of reference are used to designate similar parts throughout the specification and drawings, and in 40 which,

Fig. 1 is a broken plan view of a press platen showing the manner in which my improved guides are applied;

Fig. 2 is an enlarged side elevation of my 45 improved guide;

Fig. 3 is a front elevation of the guide as shown in Fig. 2; and

Fig. 4 is a longitudinal vertical section showing the manner in which the guide is 50 clamped into engagement with the platen sheet.

Referring to the drawings my improved guide will be seen to consist of a body 1 having a stop portion 2 formed by a plate arranged upon one end of the body at substan-

tially right angles thereto. A spring leaf 3 is secured at one end thereof to the end of the body 1 opposite the stop 2, said leaf being normally sprung away from the body 1 at its free end. The free end of the leaf 3 is slightly 60 pointed and extends past the stop 2.

A sleeve 4 is slidably mounted upon the rearward portion of the body 1 and leaf 3, said sleeve being movable to press the free end of the leaf 3 toward the body. A lug 6 65 is formed upon the rearward end of the body 1 to limit the rearward movement of the sleeve 4 and prevent said sleeve from being moved rearwardly off from the body.

A tongue 7 is slidably mounted within a lug 70 8 formed upon the under side of the body 1 slightly back of the stop 2, said tongue extending outwardly through an opening formed in the stop 2. The tongue extends rearwardly sufficiently to be engaged and 75 clamped between the leaf 3 and the body 1 when said leaf is pressed toward the body.

The stop portion 2 is made of a width greater than the body 1 and leaf 3, and has its lower edge recessed as at 9 opposite the leaf 3 to 80 form spaced extensions 11 outwardly disposed from the sides of the leaf 3.

In operation the platen sheet 12, secured in the ordinary manner upon the platen 13 of a press, is slightly slit as at 14 at the approximate points where guides are to be secured. A guide is then applied by inserting the spring leaf 3 into a slit 14, the sleeve 4 being moved rearwardly to permit said leaf to spring away from the body. The guide is then moved to 90 position the edge of the stop 2 at the exact point desired, and the sleeve moved forwardly along the leaf and body from its rearward position as indicated in dotted lines in Fig. 4, to a clamping position as indicated in full 95 lines in said figure. In thus advancing the sleeve, the leaf is pressed upwardly against the body, and the portion of the platen sheet 12 extending between the leaf and body is thus firmly clamped and the guide thereby 100

rigidly secured in the desired adjusted position. The length of the leaf 3 and body 1 is such that a relatively wide degree of adjustment is possible, as it is immaterial how far under the platen sheet the free end of the leaf 105 3 extends. In pressing the leaf toward the body to clamp the platen sheet, said sheet is forced into the recess 9 of the stop 2 and the extensions 11 caused to press slightly into the platen sheet at the sides of the leaf, thereby 110

preventing sheets of paper fed against the guide from entering under the edge of the stop.

The adjustable tongue 7 extends outwardly 5 from the stop 2 sufficiently to prevent the edges of sheets fed against the stop from being displaced and moving past the guide. The amount to which the tongue extends is 10 adjusted by sliding the tongue to a desired position while the sleeve is in its rearward position as indicated in dotted lines in Fig. 2. As the sleeve is advanced, the inner end of the tongue is engaged and clamped between the leaf and the body. This permits the 15 tongue to be readily adjusted, and at the same time permits new tongue pieces to be inserted when required.

While I have illustrated and described what I regard as the preferred construction 20 of my invention, the device is, of course, subject to modification in numerous ways without departing from the spirit of my invention. I therefore do not wish to restrict myself to the specific details of construction illustrated 25 and described, but desire to avail myself of all modifications which may fall within the scope of the appended claims.

Having thus described my invention what I claim as new and desire to secure by Letters 30 Patent is:

1. A press feed guide comprising a body having a stop arranged upon one end thereof; a spring leaf secured upon the body and arranged to be inserted through the platen 35 sheet of a press; and means slidably mounted upon the body and leaf and movable to compress the leaf toward the body to detachably clamp the platen sheet against said body.

2. A press feed guide comprising a body 40 having a stop arranged upon one end thereof; a spring leaf secured upon the body and arranged to be inserted through the platen sheet of a press; and a sleeve slidably mounted upon the body and leaf and movable to 45 press the leaf toward the body to detachably clamp the platen sheet against said body.

3. A press feed guide comprising a body having a stop arranged upon one end thereof; a spring leaf secured upon the body and 50 arranged to be inserted through the platen sheet of a press; and a sleeve slidably mounted upon the body and leaf and movable to compress the leaf toward the body to detachably clamp the platen sheet against said body; and 55 means for limiting the rearward movement of the sleeve.

4. A press feed guide comprising a body having a stop arranged upon one end thereof;

a spring leaf secured upon the body and arranged to be inserted through the platen sheet 60 of a press; and a sleeve slidably mounted upon the body and leaf and movable to compress the leaf toward the body to detachably clamp the platen sheet against said body; and a tongue slidably mounted within the stop and 65 extending outwardly therefrom, the rearward end of said tongue being adjustably clamped by the leaf.

5. A press feed guide comprising a body; a stop arranged upon one end of said body, said 70 stop consisting of a plate arranged at right angles to the plate and having a recessed bottom edge forming extensions arranged to engage the platen sheet of a press; a spring leaf secured at one end to the body and arranged 75 to be inserted through the platen sheet; and a sleeve slidably mounted upon the body and leaf and movable to compress the leaf toward the body and clamp the platen sheet against said body and into the recessed edge of the 80 stop.

6. A press feed guide comprising a body; a stop arranged upon one end of said body, said stop consisting of a plate arranged at right angles to the plate and having a recessed 85 bottom edge forming extensions arranged to engage the platen sheet of a press; a spring leaf secured at one end to the body and arranged to be inserted through the platen sheet; and a sleeve slidably mounted upon the body and leaf and movable to compress the leaf toward the body and clamp the platen 90 sheet against said body and into the recessed edge of the stop; and a tongue slidably mounted upon the body and stop and extending outwardly through the stop.

7. A press feed guide comprising a body; a stop arranged upon one end of said body, said stop consisting of a plate arranged at right angles to the plate and having a recessed 100 bottom edge forming extensions arranged to engage the platen sheet of a press; a spring leaf secured at one end to the body and arranged to be inserted through the platen sheet; and a sleeve slidably mounted upon the body and leaf and movable to compress the leaf toward the body and clamp the platen sheet against said body and into the recessed edge of the stop; and a tongue slidably mounted upon the body and stop and extending 105 outwardly past the stop, said stop being adjustably clamped against the body by the leaf.

In witness whereof, I hereunto set my signature.

WILLIAM I. NYE.
